UNITED STATES PATENT OFFICE

2,333,068

SOAP DISPENSER

William Zwanzig, Ottawa, Ill.

Application December 19, 1942, Serial No. 469,547

4 Claims. (Cl. 299—83)

The present invention relates to new and useful improvements in soap dispensers of the fluid type, and has for one of its important objects to provide, in a manner as hereinafter set forth, a device of this character which, with the addition of water, if necessary, is adapted to use soap in cake form.

Another very important object of the invention is to provide a dispenser of the aforementioned character which is adapted to conveniently receive and dispense pieces of soap or the wafers which are ordinarily thrown away, thereby preventing waste.

Still another important object of the invention is to provide a dispenser of the character described which serves as a tray for holding a cake of soap.

A still further important object of the invention is to provide a dispenser of the character set forth which is adapted to receive and retain the drainings from a cake of soap reposing in the tray, thereby further preventing waste.

Another object of the invention is to provide a soap dispenser of the fluid type comprising means whereby a piece of soap may be conveniently grated and deposited therein.

Other objects of the invention are to provide an improved soap dispenser which will be comparatively simple in construction, strong, durable, highly efficient and reliable in use, compact, and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is a view in front elevation of a soap dispenser embodying the present invention, the upper and lower portions of the device being broken away in section.

Figure 2 is a top plan view.

Referring now to the drawing in detail, it will be seen that reference numeral 1 designates a container of suitable capacity and material. Depending from the bottom of the container 1 is a conventional hand operated dispensing valve 2.

The top of the container 1 is open and removably mounted thereon is a tray 3 for the reception of a cake of soap or a portion thereof. The bottom 4 of the tray 3 has formed longitudinally therein a plurality of spaced, parallel drain slots 5.

The bottom 4 of the tray 3 is further provided with a longitudinally elongated opening 6. 55

Traversing a portion of the elongated opening 6 is a series of grating or shredding elements 7.

It is thought that the operation of the device will be readily apparent from a consideration of the foregoing. Briefly, after the cake of soap has been used, it is placed in the tray 3. The soap laden water which drips from the soap in the tray 3 drains through the slots 5 and the opening 6 into the container 1 from which it may be conveniently dispensed as desired by actuating the valve 2. Pieces of soap or wafers may be deposited in the container 1 through the unobstructed end portion of the elongated opening 6. If desired, a quantity of water may be placed in the container 1 to dissolve or assist in dissolving the soap so deposited in said container. If the wafer or piece of soap is too large, or if for any other reason it is desired to shred same, this may be conveniently accomplished in an obvious manner by scraping said soap across the elements 7.

It is believed that the many advantages of an improved soap dispenser embodying the present invention will be readily understood, and although a preferred form of the device is as illustrated and described, it is to be understood that changes in the details of construction may be resorted to which will fall within the scope of the invention as claimed.

30 What is claimed is:

1. The combination with a soap dispenser comprising a container having an opening in its top and a dispensing valve, of a tray for the reception of a cake of soap mounted on the container over the opening therein, said tray including a bottom having a drain passage therein communicating with the container.

2. The combination with a soap dispenser comprising a container having an opening in its top and a dispensing valve, of a tray, for the reception of a cake of soap, mounted on said container over the opening therein, said tray having an elongated drain passage therein communicating with the container, and shredding elements in said passage.

3. The combination with a soap dispenser comprising a container having an opening in its top and a dispensing valve, of a tray, for the reception of a piece of soap, mounted on the container over the opening therein, said tray including a bottom having an elongated drain passage therein communicating with the container, and a series of shredding elements traversing an end portion of the passage.

4. The combination with a soap dispenser com-

prising a container having an opening in its top and a dispensing valve, of a tray, for the reception of a piece of soap, removably mounted on the container over the opening therein, said tray comprising a bottom having an elongated opening therein communicating with the container, a series of shredding elements traversing a por-

tion of the opening, one end portion of said opening being free of said elements, said bottom of the tray further having a plurality of spaced drain slots therein paralleling the elongated opening on opposite sides thereof.
